SELF-OPENING PARAFFIN KNIFE FOR TUBING

Wilber H. Brite, New Orleans, La.

Application April 10, 1957, Serial No. 651,922

10 Claims. (Cl. 166—174)

This invention comprises a novel and useful self-opening paraffin knife for tubing, and more particularly relates to a paraffin cutter especially adapted for treating paraffin deposits from the interior of tubings, casings, well bores or the like.

The principal object of this invention is to provide a paraffin cleaner which may be readily inserted into the interior of well tubing, well casings, or well bores for effectively cleansing paraffin deposits from the interior thereof whereby to restore the normal rate of flow through such tubing, casing or bore.

A further object of this invention is to provide a paraffin cleaner wherein the cleansing action of the same may be effected uniformly about the entire circumference of the device.

A still further object of the invention is to provide a paraffin cleaner in accordance with the foregoing objects which may be readily applied to a string for insertion into and for removal from a tubing or the like, whereby the knife elements of the device may be normally moved into a collapsed position to permit insertion of the device into a tubing or the like, and whereby the knife elements may be readily expanded into an operative cutting position upon a withdrawing movement of the device from tubing or the like.

Yet another important object of the invention is to provide a paraffin cleaner in accordance with the above mentioned objects which shall include means limiting movement of the knife elements to their open position.

And a final important purpose of the invention is to provide a paraffin cleaner as set forth in the above mentioned objects wherein the cleaning knives may be very economically constructed of an inexpensive material such as stiff wire and may be mounted in an improved manner upon the body of the cleaning tool.

These, together with other objects and advantages which will become subsequently apparent, reside in the details of construction and operation as more fully hereinafter described and claimed, reference being had to the accompanying drawings forming a part hereof, wherein like numerals refer to like parts throughout, and in which:

Figure 1 is an elevational view showing a suitable embodiment of the paraffin cleaner incorporating therein the principles of this invention and showing the knives of the cleaner in their operative position;

Figure 2 is an end elevational view of the tool of Figure 1 showing the circumferential disposition of the series of knives about the longitudinal axis of the tool;

Figure 3 is a view in vertical section through a portion of a well tubing, and showing the manner in which the paraffin cleaner operates to strip paraffin deposits from the interior of the tubing;

Figure 4 is a view similar to Figure 3 but showing the manner in which the paraffin cleaner is introduced into a tubing for removing incrustations therefrom, with a knife element of the device being shown in its collapsed position for introduction into the paraffin-incrusted tubing; and

Figure 5 is a perspective view of the construction of a knife element forming a part of the tool.

It is a common problem in the producing of oil from formations by flow of the oil through the tubing of an oil well to contend with the deposits of paraffin which

2

form incrustations upon the interior walls of the tubing during the flow of oil therethrough. As these deposits build up, the flow of oil is materially reduced or throttled until eventually further operation of the well becomes 5 economically unsatisfactory or mechanically impossible. When this condition arises, it is necessary to remove the incrustations of paraffin before operation of the well can be continued.

Prior attempts to remove such paraffin deposits have 10 frequently employed the use of a paraffin scraper or cutter, carried by a string of rods or the like, and which is pushed down the tubing string for cleansing the paraffin deposits from the interior thereof.

It is the purpose of this invention to provide a device 15 wherein the blades or scraping elements of the paraffin cleaner may be easily introduced into a tubing string to the bottom thereof, and may then be expanded into a paraffin cutting position whereby they may be effected for cleansing paraffin from the interior of the tubing when 20 the device is pulled upwardly through the same. Cleansing a tubing string in this manner requires a less expenditure of power and is more readily performed than the above referred to conventional practice.

In the embodiment illustrated in the accompanying 25 drawings as an exemplification of the principles of this invention, the paraffin cleaner comprises an elongated rod-like body 10 which may conveniently be square in cross-section and which, at its upper end, is secured in any suitable manner to the lower end portion 12 of a 30 string such as a sucker rod string by means of which the tool may be lowered into the tubing of a well bore and may be removed therefrom. Alternatively, a wire line may be employed in place of the string 12 inasmuch as the device may be readily inserted into a tubing string by 35 gravity without the necessity for any effort being applied for forcing the device downwardly through the tubing to the bottom thereof.

Shown in Figures 3 and 4 is a section designated by 40 the numeral 14 of a string of tubing which has accumulated an incrustation of paraffin as shown at 16 and which it is desired to remove in order that flow through the tubing may be restored to the desired original volume.

Referring first to Figure 1, it will be seen that the 45 rod-like body 10 is twisted about its longitudinal axis to provide three circumferentially angularly disposed aligned sections such as those indicated at 18, 20 and 22. While any desired angular relation of these sections may be employed, it is preferred to dispose these sections at equal angular intervals.

50 Mounted upon each of these sections are a plurality of novel knife constructions each of which is designated generally by the numeral 24 and is shown best in Figure 5.

Referring now especially to Figures 3 and 4, it will be 55 seen that each of the sections of the body 10 is provided with longitudinally spaced, diametrically extending ports or bores 27. These bores may constitute passages extending entirely through the body 10, or alternatively 60 may consist of oppositely aligned bores or recesses extending into the body from opposite faces thereof. In any event there are thus provided oppositely disposed bores or recesses on opposite sides of the body into each pair of which recesses the knife element 24 is operatively mounted as set forth hereinafter.

65 Referring now especially to Figure 5, it will be seen that each of the knife elements 24 preferably comprises a member formed of a single piece of wire or similar material. Each element 24 comprises a pair of U-shaped portions having their legs angularly disposed and 70 integrally connected. Thus, the larger U-shaped portion consists of an end member 26 consisting of a straight piece of material, with a pair of legs 28 and 30 extending

therefrom. The other and smaller U-shaped portion comprises an end member 32 with a pair of legs 34 and 36 extending therefrom. The legs 28 and 34 are joined by inturned extremities each designated by the numeral 38, while the legs 30 and 36 are joined by similar inturned portions each designated by the numeral 40.

The arrangement is such that the two inturned portions 38 and 40 which join the corresponding legs of the two angularly disposed U-shaped portions of the blade 24 may be received in the pairs of oppositely disposed recesses or bores 27 whereby each of the blade members is mounted for pivotal or oscillatory movement with respect to elongated body portion 10. As will be observed from Figure 1, there are four such blades disposed on each of the sections 18, 20 and 22, whereby there are a pair of oppositely disposed blades for each of the opposite surfaces of that section. The lengths of the U-shaped sections of each blade are such that when the blades are mounted as shown in Figures 3 and 4, the smaller U-shaped section is adapted to embrace the body portion 18, 20 or 22 and if desired may limit closing movement of the blades, this being the movement in the direction indicated by the arrows 42 and 44 to the position shown in Figure 4. This will be the position normally assumed by the blade as the tool is moved downwardly in the tubing as shown by the arrow 46. This may be considered to be the closed or collapsed position of the blades.

However, the larger U-shaped portion of the blades will by its gravity tend to open the blades to the position shown in Figure 3, and which is the position whereby the ends 26 of the blades will engage the interior of the tubing 14 and scrape the paraffin incrustation 16 therefrom when the tube is withdrawn as shown by the arrow 48 in Figure 3.

If desired, the length of the legs 34 and 36 of the smaller U-shaped portion may be such as to cause the end portion 32 thereof to abut the body 10 and thus limit both the opening and the closing pivotal movement of the blades. However, it is preferred to provide cross bars 50 welded or otherwise secured to the opposite sides of the body 10 to constitute stops, as shown in Figure 3, to limit the opening movement of the blades.

By the longitudinal spacing of the blades along the three circumferentially twisted sections of the elongated body, there is provided for each section a cutting blade having a cutting edge 26 disposed in each of the four surfaces of that section of the body, whereby, as shown in Figure 2, all of the cutting edges 26 will overlap to thus scrape paraffin from the entire interior circumference of the tubing.

It will be understood that this construction may also be employed to scrape paraffin from the interior of a casing or even from the wall of a well bore in some instances.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to falling within the scope of the invention as claimed.

What is claimed as new is as follows:

1. A paraffin cleaner for scraping paraffin accumulations from the interior of tubings or casings and well bores comprising an elongated body adapted for insertion and longitudinal travel in a tubing or casing, a plurality of longitudinally spaced, diametrically disposed bores in opposite sides of said body, a plurality of scraper blades each comprising a pair of U-shaped rod-like sections rigidly joined at their legs and having pivot members secured at their leg joints received in said bores for pivotal movement between a position wherein at least one of said sections is collapsed against said body for

insertion in a string of tubing and an extended position for scraping paraffin from the wall of a tubing string when drawn through the latter, the legs of said scraper blades being at least of a sufficient length to extend from said pivot members to the interior wall of the tubing in which the cleaner is disposed, the legs of each scraper being so arranged that when one section contacts the tubing wall, the other section will engage said body and prevent pivoting of the blade past a position in which it engages the tubing wall.

5 2. The combination of claim 1 wherein said elongated body has a plurality of circumferentially angularly disposed sections, a plurality of blades mounted on each section whereby to cover substantially the entire circumference with overlapping blades.

15 3. The combination of claim 1 including a plurality of transverse bars each secured to said body adjacent one of said blades and providing a stop engageable with a blade for limiting pivotal movement of said blade in its extended position.

20 4. The combination of claim 1 wherein the U-shaped sections of each blade are of different lengths with the longer section being gravity actuated to its extended position.

25 5. The combination of claim 1 wherein the joined legs of the U-shaped sections of each blade are angulated.

6. The combination of claim 1 wherein the legs of said U-shaped sections of each blade have inturned joined ends disposed in side-by-side relation and comprising

30 30 said pivot members.

7. The combination of claim 1 wherein each blade comprises a single piece of wire.

8. A paraffin cleaner for scraping paraffin deposits from the interior of a conduit comprising an elongated

35 body of a size and shape to enable its insertion and longitudinal travel in a conduit, a plurality of scraper blades each pivotally connected to said body for vertical swinging movement about an axis lying transversely of said body, each blade including an open U-shaped section of

40 rod-like character having a pair of legs disposed in side-by-side relation on opposite sides of said body and a web portion connected to said legs and extending therebetween and comprising a scraping element engageable

45 with the wall of said conduit, said pair of legs being of a length at least equal to the distance of their pivot point to the interior wall of said conduit, said body having oppositely disposed diametrical bores, said legs having inturned portions comprising pivot means received in said bores, said blades being pivotable about said pivot means

50 between an extended position in which said web is engageable with said conduit and a retracted position with said web disposed against said body, a stop bar extending transversely of and secured to the body adjacent each of said blades in position for engagement by the legs of the latter when said blades are in their extended position.

55 9. The combination of claim 8 wherein said blades are disposed in successive longitudinally and circumferentially spaced positions on said body with the webs of said blades overlapping whereby to scrape the entire circumference of said conduit.

60 10. The combination of claim 8 wherein said blades each include a second U-shaped section disposed on the opposite side of the body from the first mentioned section and rigidly secured to the latter, said second section having its legs shorter than those of the first mentioned section whereby the web of said second section will contact said elongated body and prevent the second section from swinging past the dead center positions of said sections.
